US00D883512S

(12) **United States Design Patent** (10) **Patent No.:** **US D883,512 S**
(45) **Date of Patent:** **** May 5, 2020**

(54) **MORTAR**

(71) Applicant: **Suzhou Ewayt Network Technology Co., Ltd.**, Suzhou (CN)

(72) Inventor: **Min Zhou**, Suzhou (CN)

(73) Assignee: **Suzhou Ewayt Network Technology Co., Ltd.**, Suzhou (CN)

(**) Term: **15 Years**

(21) Appl. No.: **29/717,491**

(22) Filed: **Dec. 17, 2019**

(51) LOC (12) Cl. **24-02**

(52) U.S. Cl.

USPC **D24/220**

(58) **Field of Classification Search**

USPC D24/220; D14/189; D7/682

CPC A61J 7/0007

See application file for complete search history.

(57) **CLAIM**

I claim the ornamental design for a mortar, as shown and described.

DESCRIPTION

FIG. 1 is front elevational view of a mortar showing my new design;

FIG. 2 is a rear elevational view thereof;

FIG. 3 is a left side elevational view thereof;

FIG. 4 is a right side elevational view thereof;

FIG. 5 is a cross-sectional view of the mortar taken along the line 5-5 in FIG. 3;

FIG. 6 is a top plan view of FIG. 1; and,

FIG. 7 is a bottom plan view thereof.

The shade lines in the Figures show contours and form no part of the claimed design.
